US00D702162S

(12) **United States Design Patent**
Heilaneh et al.

(10) **Patent No.:** **US D702,162 S**
(45) **Date of Patent:** **** Apr. 8, 2014**

(54) **VEHICLE BUMPER COMPONENT**

(71) Applicants: **Louis D. Heilaneh**, Lewisville, TX (US); **Derek Sancer**, Corinth, TX (US); **Chris I. Ito**, Sugar Grove, IL (US); **Kunjithapadam Raghavendran**, Denton, TX (US); **William J. Johnson**, Dallas, TX (US); **Scott D. Hite**, Pilot Point, TX (US)

(72) Inventors: **Louis D. Heilaneh**, Lewisville, TX (US); **Derek Sancer**, Corinth, TX (US); **Chris I. Ito**, Sugar Grove, IL (US); **Kunjithapadam Raghavendran**, Denton, TX (US); **William J. Johnson**, Dallas, TX (US); **Scott D. Hite**, Pilot Point, TX (US)

(73) Assignee: **PACCAR Inc**, Bellevue, WA (US)

(**) Term: **14 Years**

(21) Appl. No.: **29/449,163**

(22) Filed: **Mar. 14, 2013**

(51) LOC (10) Cl. **12-16**

(52) U.S. Cl.

USPC **D12/169**

(57) **CLAIM**

The ornamental design for a vehicle bumper component, as shown and described.

DESCRIPTION

FIG. 1 is a top perspective view of a vehicle bumper component for a vehicle according to our new design;

FIG. 2 is a bottom perspective view of the vehicle bumper component of FIG. 1

FIG. 3 is a front view of the vehicle bumper component of FIG. 1;

FIG. 4 is a left side view of vehicle bumper component of FIG. 1;

FIG. 5 is a right side view of vehicle bumper component of FIG. 1;

FIG. 6 is a top view of the vehicle bumper component of FIG. 1; and,

FIG. 7 is a bottom view of the vehicle bumper component of FIG. 1.

The rear of the vehicle bumper component is unornamented. The broken lines of FIGS. 1 and 2 are for illustrative purposes only and forms no part of the claimed design.

1 Claim, 4 Drawing Sheets
